UNITED STATES PATENT OFFICE

164,480

FISH BOWL

Frank Dostalek, Erie, Pa.

Application October 5, 1950, Serial No. 12,454

Term of patent 14 years

(Cl. D91—2)

To all whom it may concern:

Be it known that I, Frank Dostalek, a citizen of the United States, residing at Erie, in the county of Erie and State of Pennsylvania, have invented a new, original, and ornamental Design for a Fish Bowl, of which the following is a specification, reference being had to the accompanying drawing, forming part thereof.

Fig. 1 is a front view of the back plate of the fish bowl with the front removed, and Fig. 2 is a side elevation of the fish bowl. The dominant feature of my design resides in the portions shown in full solid lines.

I claim:

The ornamental design for a fish bowl, as shown and described.

FRANK DOSTALEK.
